UNITED STATES PATENT OFFICE.

JAMES WIGHTMAN, OF PITTSBURG, PENNSYLVANIA.

IMPROVEMENT IN STEAM-BOILERS.

Specification forming part of Letters Patent No. **81,102**, dated June 13, 1854.

To all whom it may concern:

Be it known that I, JAMES WIGHTMAN, of the city of Pittsburg, in the county of Allegheny and State of Pennsylvania, have invented certain new and useful Improvements in Steam-Boilers especially adapted for Marine Steam-Engines, of which the following is a full, clear, and exact description, reference being had to the accompanying drawings of the same, which makes part of this specification, and in which—

Figure 1 represents a longitudinal section of a boiler having my improvements applied thereto. Fig. 2 represents a transverse section of the same at the line 1 1 of Fig. 1; and Fig. 3 represents a transverse section at the line x x of Fig. 1, the red lines representing the boiler on a vessel when careened to show the relative position of the flues and water-line under such circumstances.

The object of my invention is to combine the advantages of cheapness of construction and facility of cleaning and repairing which the flue-boiler embraces with the advantage of great heating-surface exposed by a comparatively small quantity of water which the tubular boiler presents, and at the same time avoid the difficulties of cleaning and repairing, from which the tubular boiler is never free, and the necessity for carrying and heating a great weight of water for no other purpose than to fill up useless spaces between and below the large end flues in the flue-boiler as heretofore constructed.

The object of my invention is, further, to maintain a constant distance between the top of the flues and the surface of the water, whether the vessel on which the boiler is carried be on an even keel or careened.

The external shell of the boiler and furnace may be made of the usual form. The interior of the fire-box is also of the usual form, but its arch or roof A, instead of terminating as usual in flue or tubular boilers at a flue-sheet at the back of the fire-box, it extends through to the rear end of the boiler, where it terminates at the flue-sheet B, forming the front side of the smoke - box or uptake-flue. A counter-arch, C, is connected with the arch A, leaving an included space to form a flue whose transverse section corresponds in outline to that of a short and thick elliptical

spindle. This counter-arch extends from the bridge D to the rear side, L, of the uptake, and is placed a short distance above the bottom E of the cylindrical part of the boiler, and is concentric therewith, leaving a narrow water-space, F, between the two. This spindle-shaped flue made in this manner gives a very great area for its height, and permits the flame to enter it so freely, and so much of its upper arch is exposed to the direct radiation of heat from the fuel upon the grate, that its heating-power is much greater than that of ordinary flues, and is nearly equal in this respect to the fire - surface of the furnace. Above this direct spindle-flue a series of return-flues, G, are arranged in an arc of a circle concentric with the arch A of the fire-box and direct flue. These flues are for the purpose of conducting the smoke and flame from the uptake H to the chimney I, and while doing so to transmit the heat from the gases and flame passing within them to the water in the boiler lying in contact with their outsides. These flues G terminate at one end in the front head, J, of the boiler, and at the other in the flue-sheet B on the front of the uptake-flue H.

The radius of curvature in which the flues G are arranged is such that if the vessel should careen the extreme position in which her deck would stand at an angle of thirty degrees to the horizon, the tubes would not even then be uncovered. This will protect the boiler effectually against the overheating of the flues in consequence of being uncovered when the vessel careens, which is believed by many to be the most fruitful cause of explosions of boilers on steamboats of the western and southern rivers.

The arch A and counter-arch C may be connected by a series of vertical tubes, K, to strengthen them against collapsing, or they may be stayed by radial bolts M, connecting them with the external shell, as represented by red lines; or both these methods of staying the arches may be employed together, as in the judgment of the constructor may be deemed most expedient.

For the purpose of collecting the sediment deposited from the water and drawing it out of the boiler more readily, a mud-leg may be connected with the rear end of the bottom of

the shell, in the lower end of which a blow-off cock may be set in the usual manner.

With fire box and flues constructed and arranged in the shell as described, there is a thin sheet of water surrounding the whole of the fire and flue surfaces, with a sufficient quantity above the flues to supply the evaporation, so that in case the feed-pump should cease to operate for a short time there would be no danger of the water suddenly getting too low; but except that part of the body of water marked N to form a necessary supply at the upper part of the boiler there is elsewhere barely a sheet of water surrounding the flue and fire surfaces of sufficient thickness to conduct away the heat, so that a vessel fitted with this boiler would not be loaded with superfluous water, which is a matter of great consequence in the navigation of shallow and rapid rivers where it is necessary to obtain the greatest possible power with the least possible weight of boiler.

Having thus described my improved steam-

boiler, what I claim therein as new, and desire to secure by Letters Patent, is—

The arrangement of the arch or roof of the fire-box extending through to the uptake and connected with a counter-arch in such manner as to form an elliptical flue to form a communication between the furnace and uptake in connection with a series of small return-flues above the roof of the fire-box and elliptical flue, and in a curve concentric therewith, so that the upper side of the highest flue will be at the same distance, or thereabout, below the upper surface of the water within the boiler, whether the latter be upright, as when a vessel on which it is placed is on an even keel, or inclined, as when the vessel is careened, substantially as set forth herein.

In testimony whereof I have hereunto subscribed my name.

JAMES WIGHTMAN.
